UNITED STATES PATENT OFFICE.

JAMES HARRISON WOODWARD, OF SEWARD, NEBRASKA.

THERAPEUTIC ELECTRODE.

SPECIFICATION forming part of Letters Patent No. 390,544, dated October 2, 1888.

Application filed November 21, 1887. Serial No. 255,797. (No model.)

To all whom it may concern:

Be it known that I, JAMES HARRISON WOODWARD, a citizen of the United States, and a resident of Seward, in the county of Seward and State of Nebraska, have invented certain new and useful Improvements in Electrodes; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of my new and improved electrode. Fig. 2 is a perspective view of the same, showing it covered with a sponge cap. Fig. 3 is a longitudinal central sectional view of the electrode and its insulated handle; Fig. 4, a top view of the electrode. Fig. 5 is a detail view of the sponge cap, and Fig. 6 is a vertical sectional view showing the metal cup provided with a hard-rubber rim along its edges.

The same letters of reference indicate corresponding parts in all the figures.

My invention consists in a new and improved electrode which is designed to be employed to transmit a volatile substance—such as chloroform, ether, &c.—by means of an electric current, into a diseased part of the body for the cure of local diseases, such as neuralgia, rheumatism, sciatica, &c.; and my invention will be hereinafter fully described and claimed.

Referring to the several parts by letter, A indicates a piece or block of carbon, which is set in a metal cup, B, on the center of the back of which metal cup is formed or soldered a screw, C. The outer face of this porous carbon plate or block A is slightly concave or hollowed out, as clearly shown in the sectional view, so that it will hold the volatile substance to be absorbed, and thus more readily absorb the same. When used with a battery, a handle, D, consisting of a metal tube is used, the screw C on the back of the metal cup of the electrode being screwed into one end of the said metal tubular handle, and this metal handle is insulated by a covering or tube, E, of either soft or hard rubber. The tip of the conducting-wire from the battery is secured in the other end of the metal handle D by the set-

screw F, which will hold the said tip in place in the end of the handle.

The carbon is porous in its formation, and will readily absorb any volatile substance and become thoroughly saturated with the same, and will then slowly give the said substance off again. The substances most readily absorbed by the carbon are chloroform, ether, alcohol, most of the tinctures, and some of the oils.

The mode of operation is as follows: The volatile substance which it is desired to transmit into the diseased part of the body is placed on the slightly-hollowed porous carbon, which will readily absorb the same, and when sufficiently charged with the substance the electrode is applied to the diseased part, the electric current being turned on, when the electric current passing through the saturated positive electrode in the direction of the diseased part, the osmotic power of the absorbent vessels are increased and the medicine in a volatile form is carried by the electric current from the saturated carbon electrode to the part diseased. The medicine is thus introduced into the system physiologically, in contradistinction to introducing medicines into the system hypodermically or mechanically.

By the use of my new and improved electrode, employed as described, all local diseases can be successfully treated—to wit, neuralgia, rheumatism, sciatica, local inflammations of the bowels, stomach, kidneys, and spine.

In ordinary cases the carbon electrode is covered with a sponge, H, which is formed into a cap, as shown in the drawings, by stitching a soft piece of leather, I, around its lower side, the said leather piece being formed with the two end tongues, J J, which extend on each side of the handle when the sponge cap is placed in position on the electrode, and buckle into small buckles K K, which are secured to a leather strip, L, which is stitched to the flap formed at that side of the sponge cap, as shown in the drawings. It will be seen that by forming the sponge cap in this manner it can be readily and firmly secured in a moment over the carbon electrode by buckling the ends of the tongues J J in the small buckles K K, when the sponge cap will be held firmly in position in and over the electrode, and there will be no

danger of its slipping off while in use. In special painful diseases the sponge is removed and the carbon electrode applied to the diseased part without any covering. The metal cup can be formed with an edge flange or rim, which will hold the carbon in position in the cup; or this metal rim may be dispensed with and the metal cup formed with a hard-rubber rim, B', to insulate the edges of the carbon electrode. This rubber rim to the cup will be found especially useful when the electrode is to be applied without the sponge cap, as it will prevent the metal of the cup from coming into direct contact with the flesh of the patient.

15 When my new and improved carbon electrode is to be used in a belt instead of with a battery, as before described, the handle is of course dispensed with, and the electrode is secured to the positive end of the electric belt by a suitable screw and tap.

Instead of the sponge cap, the electrode may be covered with a cap of chamois-skin, secured over the electrode in substantially the same manner, so that it can be readily removed.

25 From the foregoing description, taken in connection with the accompanying drawings, the construction, operation, and many advantages of my new and improved electrode will be readily understood. It will be seen that by 30 means of the porous carbon electrode seated in

the metal cup and having the insulated handle the volatile substances can be readily and effectively transmitted to the diseased part of the body.

Having thus described my invention, what 35 I claim, and desire to secure by Letters Patent of the United States, is—

1. The combination of the carbon electrode secured in the metal cup, having a screw on its back, and the metal handle having the threaded 40 end and the set-screw and covered by the rubber sleeve or tube, substantially as set forth.

2. The combination of the carbon electrode formed with the concave outer face, the metal cup having the screw on its back, and the 45 tubular metal handle having the threaded end and the set screw and covered by the rubber sleeve or tube, substantially as set forth.

3. The combination, with the herein-described electrode, of the cap of soft porous material having the buckles and straps for securing it in position removably over the carbon electrode, substantially as set forth.

In testimony that I claim the foregoing as my own I have hereunto affixed my signature in 55 presence of two witnesses.

JAMES HARRISON WOODWARD.
